UNITED STATES PATENT OFFICE.

ARTHUR PLANTIER, OF TRENTON, NEW JERSEY.

DESIGN FOR A SIPHON-JET CLOSET.

SPECIFICATION forming part of Design No. 31,048, dated June 20, 1899.

Application filed May 11, 1899. Serial No. 716,442. Term of patent 14 years.

To all whom it may concern:

Be it known that I, ARTHUR PLANTIER, residing at Trenton, in the State of New Jersey, have invented and produced a new and original Design for a Siphon-Jet Closet, of which the following is a description, accompanied by an illustrative drawing of the design.

In the drawings, Figure 1 is a perspective and Fig. 2 a rear end view of a closet embodying the design.

The new, useful, and original shape or configuration which constitutes my design resides mainly in the rounded shape *j* of the jet-passages at each side of the upper part of the siphon-inclosing portion *s* of the closet. These jet-passages after passing the level of

the dome of the siphon turn in toward each other and merge their external surfaces into nearly flat surfaces at the sides of the siphon at *f*. This results in an exterior surface especially free from recesses and sudden projections.

What I claim, and desire to secure by these Letters Patent, is—

The design for a siphon-jet closet, substantially as shown and described.

Signed this 21st day of April, 1899, at Trenton, New Jersey.

ARTHUR PLANTIER.
